(57) CLAIM

The ornamental design for a drinking vessel, as shown and described.

DESCRIPTION

FIG. 1 is a top front perspective view of a drinking vessel showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a cross-sectional view taken along 8-8 of FIG. 6;

FIG. 9 is a top front perspective view of an alternative embodiment of a drinking vessel showing our new design;

FIG. 10 is a front view thereof;

FIG. 11 is a rear view thereof;

FIG. 12 is a right side view thereof;

FIG. 13 is a left side view thereof;

FIG. 14 is a top view thereof;

FIG. 15 is a bottom view thereof; and,

FIG. 16 is a cross-sectional view taken along 16-16 of FIG. 14.

The even-length broken lines depicting of the unshaded elements of the drinking vessel in FIGS. 8 and 16 show features that form no part of the claimed design. The uneven-length broken lines depicting the remainder of the drinking vessel in FIGS. 6 and 14 show features that form no part of the claimed design.
